UNITED STATES PATENT OFFICE

HOWARD M. CHAMBERS, OF FLINT, MICHIGAN, ASSIGNOR TO MARVEL CARBURETER COMPANY, OF FLINT, MICHIGAN, A CORPORATION OF INDIANA

HEAT CONTROLLING MEANS FOR CHARGE FORMING DEVICES

Application filed November 10, 1926. Serial No. 147,520.

This invention relates to certain new and useful improvements in heat controlling means for charge forming devices used in connection with internal combustion engines, the object being to provide means for controlling the application of heat to a nicely so that a highly efficient explosive charge can be formed without any danger of overheating the charge under the different atmospheric 10 conditions.

Another object of my invention is to provide a heat controlling means in which the exhaust gases are throttled and caused to circulate through a heating jacket surrounding the induction pipe and throttle chamber of the charge forming device, means being provided and controlled from the dash of the motor vehicle to which the device is attached for setting the same in order to apply 15 the proper amount of heat irrespective of the movement of the throttle valve.

Another object of my invention is to provide a construction in which the exhaust manifold is provided with an exhaust throttling valve so as to divert the exhaust gases out of their natural path of travel through the heating chamber for the explosive charge, said exhaust valve being operated by the 20 throttle valve of the charge forming device so that as the throttle valve is moved, the exhaust throttling valve will also move whereby the application of heat is controlled by various settings from the dash controlled means.

Another and further object of the invention is to provide novel means for changing the centers of the linkage and operating levers connecting the exhaust throttling valve to the charge throttling valve in order to 25 allow the exhaust valve varying degrees of opening and to provide means for allowing the charge throttle valve to open wide at full charge throttle irrespective of the position of the dash controlling means.

A still further object of the invention is to provide a heat controlling means which is very simple and cheap in construction, the parts being so arranged and mounted that all danger of the same getting out of order in 30 operation is prevented.

Another object of my invention is to provide in connection with the exhaust throttling valve, a valve connected thereto for controlling the outlet of the heating chamber for the explosive charge.

A still further object of the invention is to provide a novel form of intake manifold and heating chamber therefor in conjunction with the heating chamber around the throttle of the charge forming device.

Other and further objects and advantages of the invention will be hereinafter set forth and the novel features thereof defined by the appended claims.

In the drawings,

Figure 14 is a vertical section showing the flow of exhaust gases through the heating chamber for heating the explosive charge in its passage to the engine;

Figure 16 is a side elevation of the intake manifold;

Figure 15 is a vertical section through the exhaust manifold, intake manifold and a portion of the charge forming device; and

Figure 17 is a top plan view of an intake manifold constructed in accordance with my invention.

15 In the drawings 1 indicates an internal combustion engine, 2 an exhaust manifold, 3 an intake manifold and 4 a charge forming device.

The exhaust manifold 2 is provided with 20 branches 5, 6, 7 and 8 which are adapted to be connected to the exhaust ports of the internal combustion engine and through which the exhaust gases are adapted to pass to a muffler, not shown, through a pipe 9. The 25 exhaust manifold 2 has a central enlargement 10 to provide an outlet passage 11 and an inlet passage 12, said inlet passage communicating with a longitudinally disposed passage 13 which is in communication with 30 the main passage 14 of the exhaust manifold through a triangular opening 15 for the purpose hereinafter fully described. From the above description it will be seen that I have formed an exhaust manifold divided to form 35 passages which are in communication with each other through a valve controlled opening.

The intake manifold 3 is provided with a 40 central induction passage 16 terminating at its upper end in a chamber 17 from which extend oppositely disposed branches 18 and 19 terminating in right angle ends 20 and 21 adapted to be connected to the respective intake ports of the internal combustion engine. 45 A central branch 22 extends from the chamber 17 which terminates in nipples 23 and 24 adapted to be connected to the respective intakes of the internal combustion engine whereby the explosive charge produced in the 50 charge forming device 4 is delivered to the respective intake ports of the internal combustion engine.

The induction passage of the intake manifold is surrounded by heating chambers 25 and 26 on the opposite sides of the manifold and the heating chambers are constructed to conform to the shape of the enlargement of the exhaust manifold so that the exhaust gases will circulate down the heat chamber 26 and up the heat chamber 25 as will be more fully described, the two manifolds being connected together by any suitable means, such as bolts and the like.

65 The charge forming device is provided at its upper end with a heat chamber 27 adapt-

ed to register respectively with the heat chambers 25 and 26 so that as the exhaust gases circulate down through one of the heating chambers of the intake manifold, they pass into the heating chamber 27 of the charge forming device and circulate through the same and up the other heating chamber of the intake manifold into the exhaust manifold through the inlet 12 into the passage 13 and out the opening 15 into the main passage 14 of the exhaust manifold. It, of course, is understood that the valves, which will be hereinafter fully described, are in such a position as to allow the gases to flow in this manner.

The exhaust manifold opposite the opening 15 has a circular opening formed in its wall which is closed by a cover plate 28 to provide means for inserting and removing an exhaust throttling valve 29 which is provided with a hub portion 30 fixed on a stem 31 mounted in a bushing 32 arranged within a boss 33 formed on the exhaust manifold as clearly shown in Figure 4.

The exhaust throttling valve 29 controls 90 the passage of exhaust gases through the main exhaust passage and is preferably in the form of a wing valve, one of the wings being provided with a substantially triangular plate 34 forming a valve for the opening 15 95 for controlling the passage of exhaust gases through the other exhaust passage of the manifold so that the outlet in the heating chamber of the intake manifold will be controlled through the medium of this valve as the exhaust throttling valve is opened and closed, the position of the plate in respect to the wings of the valve being clearly shown in Figures 5a to 8a in the various positions the valve assumes as it is opened by the movement of the charge throttling valve.

In order to allow the exhaust throttling valve to dwell on its seat or to remain in closed position during a portion of its movement, the opposite walls of the passage of the exhaust manifold are provided with shoulders 35 and 36, the size of which determine the opening and closing of the valve as by lengthening these bosses, the valve will dwell on its seat for a greater length of time and by shortening these bosses or shoulders, the valve will open or forced to dwell on its seat. The movement of the valve and the dwelling of the same is clearly illustrated in Figures 5a and 6a of the drawings.

110 Mounted on the outwardly extending end of the valve stem 31 is a bell crank 37, one arm of which is connected by a link 38 to an adjusting lever 39 mounted on the dash adjusting plate bearing the following designations: "Heat on" "Medium" and "Heat off" whereby the adjustment of the lever 39 shifts the position of the bell crank as will be hereinafter fully described.

115 Disposed between the end of the boss 33 120

and the bell crank is a frictional washer 40 for preventing the bell crank moving with the arm 44 when operated as will be hereinafter fully described.

- 5 Fixed on the end of the valve stem 31 is a slotted lever 41 for operating the exhaust throttling valve, a coil spring being arranged around the valve stem, the opposite ends of which engage washers 42, one of which bears 10 against the slotted lever and the other against the bell crank so as to hold the bell crank in frictional engagement with the boss of the exhaust manifold so as to prevent the bell crank from being operated as the lever 41 is 15 operated in opening and closing the exhaust throttling valve.

Pivotaly mounted on the opposite end of the bell crank lever 37 by frictional means as shown at 43 is an arm 44 which carries at its 20 free end a double-ended pin 45, one end of which carries a roller 46 slidably mounted in the slot of the lever 41 and the other end carries an adjustable connection 47 to which is adjustably connected a rod 48 which has 25 its other end connected to an arm 49 fixed on a valve stem 50 on which is mounted a charge throttle valve 51 for the charge forming device, the bell crank 37 being provided with a stop A which is adapted to engage a pin B for limiting the movement of 30 the bell crank.

The arm also carries the usual connecting rod 52 extending to the body of the motor vehicle and controlled by the usual 35 means for controlling the position of the throttle and charge forming device and the particular construction of throttle valve and manner of operating the same and the charge forming device is immaterial so long as a lever is employed for rocking the valve in order that the movement of the lever will impart movement to the exhaust throttling valve through the medium of the links and levers so as to vary the throw of the movement 40 of the exhaust throttling valve in respect to the charge throttling valve whereby the mechanism may be set from the dash in order to control the application of the heating medium, which is in the form of exhaust gases, to the heating chamber to a 45 nicety.

In the diagrammatic views illustrated in 50 Figures 5, 6, 7, 8, 5a, 6a, 7a and 8a I have shown a dash controlled lever set in various positions so as to adjust the center of the pin in respect to the fulcrum of the operating lever of the exhaust throttling valve whereby the exhaust throttling valve may be caused to dwell on its seat for a greater or 55 shorter length of time.

In the operation of the device, any movement of the dash controlled lever is communicated first to the bell crank lever, then 60 through the idling arm 44 carrying a pin and roller so as to cause the roller to move

up and down in a slot of the exhaust throttling valve lever thus shortening and lengthening the actual working center to center distance between roller and exhaust throttle valve shaft. This change of center allows the 70 exhaust throttle valve various degrees of opening and the slot in the exhaust throttle lever is so located that this variation comes at the closing end of the charge throttle valve movement, allowing the exhaust throttle valve to open wide at full charge throttle no matter at what position the dash control is set, but keeping it from closing entirely when the dash control is set for 75 medium or heat off in warm weather or when the motor is warmed up. This construction provides means for varying the effect of movement of the charge controlling valve on the exhaust controlling valve, whereby the 80 application of heat to the heating chamber of the induction pipe can be controlled to a nicety.

From the foregoing description it will be seen that I have provided a heat controlling means for charge forming devices in which the exhaust manifold is provided with parallel passages in communication with each other through an exhaust valve controlled opening so as to provide means for causing the exhaust gases passing through said exhaust manifold to be diverted out of their natural path of travel through a heating chamber surrounding the induction pipe of the charge forming device whereby the explosive charge can be heated and in connection with the dash controlling means the application of heat can be controlled to a nicety, as by adjusting the dash control means the effect of movement of the charge controlling valve on the exhaust control valve can be varied so as to prevent overheating of the charge in its passage to the engine.

What I claim is:—

1. The combination with an internal combustion engine having an exhaust passage, intake manifold and charge forming device connected thereto, of a heater for heating the charge in its passage to the engine, a shaft carrying an exhaust throttle valve for controlling the passage of exhaust gases to said heater, a charge throttle valve for controlling the passage of explosive charge to said engine, a slotted lever fixed on said shaft for operating the exhaust throttling valve, a member slidably mounted in said lever, a connection between said charge throttling valve and said member and means for adjusting said member towards and away from the fulcrum of said lever to vary the effect of movement of the charge controlling valve on the exhaust controlling valve.

2. The combination with an internal combustion engine having an exhaust passage, intake manifold and charge forming device

- connected thereto, of a heater for heating the charge in its passage to the engine, a throttle valve mounted in the exhaust passage for controlling the passage of exhaust gases to said heater, a valve stem for said valve, a slotted lever fixed on said valve stem, a valve controlling the passage of explosive charge to said engine, a member slidably mounted in said slotted lever, a connection between said member and the charge throttling valve and means for adjusting said member in the slot of said lever to vary the effect of movement of the charge controlling valve on the exhaust controlling valve.
3. The combination with an internal combustion engine having an exhaust passage, intake manifold and charge forming device connected thereto, of a heater for heating the charge in its passage to the engine, an exhaust throttling valve for controlling the passage of exhaust gases to said heater, said valve having a valve stem carrying a slotted arm, a valve controlling the passage of explosive charge to said engine, a bell crank lever mounted freely on said exhaust throttling valve stem, dash controlled means connected to said bell crank lever, an arm pivotally mounted on said bell crank lever, a pin carried by said arm working in said slotted lever and a connection between said pin and the charge throttling valve.
4. The combination with an internal combustion engine having an exhaust passage, intake manifold and charge forming device connected thereto, of a heater for heating the charge in its passage to the engine, an exhaust throttle valve for controlling the passage of exhaust gases to said heater, said throttling valve being provided with a valve stem having a slotted arm fixed thereon, a throttle valve for controlling the passage of explosive charge to said engine, a bell crank lever loosely mounted on said exhaust throttling valve stem, an arm pivotally mounted on said bell crank lever, a member carried by said arm slidably mounted in the slot of said lever, a connection between said member and said charge controlling valve and means for operating said bell crank lever to adjust said member in the slot of said lever to vary the effect of movement of the charge controlling valve on the exhaust controlling valve.
5. The combination with an internal combustion engine having an exhaust passage, intake manifold and charge forming device connected thereto, of a heater for heating the charge in its passage to the engine, said exhaust passage having a valve stem mounted therein carrying a valve for controlling the passage of exhaust gases to said heater, an arm fixed on said valve stem provided with a slot, a valve for controlling the passage of exhaust gases to said engine, a bell crank lever loosely mounted on said valve

stem, an arm loosely mounted on one of the arms of said bell crank lever, a member carried by the free end of said arm extending into the slot of said lever, dash controlled means connected to the other arm of said bell crank lever and a connection between said arm and said charge controlling valve.

6. The combination with an internal combustion engine having an exhaust passage, intake manifold and charge forming device connected thereto, of a heater for heating the charge in its passage to the engine, a throttle valve for controlling the passage of exhaust gases to said heater, said throttle valve being carried by a valve stem having a slotted arm fixed therein, a valve for controlling the passage of explosive charge to said engine, said last-mentioned valve being carried by a valve stem having a lever fixed thereon, a member slidably mounted in the slotted lever of said exhaust controlling valve, a connection between said member and the lever of the charge controlling valve and dash controlled means for adjusting said member in the slot of said lever to vary the effect of movement of the charge controlling valve on the exhaust controlling valve.

7. The combination with an internal combustion engine having an exhaust passage, intake manifold and charge forming device connected thereto, of a heater for heating the charge in its passage to the engine, said exhaust passage being provided with an auxiliary exhaust passage in communication therewith through a valve controlled opening, a double exhaust throttle valve mounted in said exhaust passage for controlling the passage of exhaust gases therethrough and the exhaust gases from said auxiliary passage for controlling the passage of exhaust gases to said heater and from said heater, a valve stem upon which said exhaust valve is mounted, a slotted arm fixed on said exhaust valve stem, a charge throttling valve for controlling the passage of explosive charge to said engine, a sliding connection between said valve and said arm and means for adjusting said connection to vary the effect of movement of the charge controlling valve on the exhaust controlling valve.

8. The combination with an internal combustion engine having an exhaust manifold, intake manifold and charge forming device connected thereto, of a heater in communication with the exhaust manifold for heating the charge in its passage to the engine, a throttle valve for controlling the passage of exhaust gases to said heater, a throttle valve for controlling the passage of explosive charge to said engine, a lever for operating said exhaust throttling valve, a member having a sliding connection with said lever, a connection between said member and said charge throttling valve and dash controlled

means for adjusting said member on said lever to vary the effect of movement of the charge throttling valve on the exhaust throttling valve.

5. 9. The combination with an internal combustion engine having an exhaust manifold, intake manifold and charge forming device connected thereto, of a heater for heating the charge in its passage to the engine, said heater 10 being in communication with the exhaust manifold, a valve for controlling the passage of exhaust gases to and from said heater, said valve being carried by a valve stem having a slotted arm fixed thereon, a bell crank lever 15 loosely mounted on said valve stem, an arm pivotally mounted on one of the arms of said bell crank, a member carried by said arm working in the slot of said lever, a connection between said arm and the charge controlling 20 valve and dash controlled means having a connection with the other arm of said bell crank for adjusting the position of said member within the slot of said lever through the medium of said arm to vary the effect of 25 movement of the charge controlling valve on the exhaust controlling valve.

10. The combination with an internal combustion engine having an exhaust passage, intake manifold and charge forming device 30 connected thereto, of a heater for heating the charge in its passage to the engine, said exhaust passage being provided with oppositely disposed projections to form a valve seat, a throttle valve mounted in said exhaust passage and cooperating with said valve seats for controlling the passage of exhaust gases to 35 said heater, a valve controlling the passage of explosive charge to said engine, a slotted lever for operating the exhaust throttling valve, a member slidably mounted in the slot of said 40 lever, a connection between said charge throttling valve and said member and means for adjusting said member in the slot of said lever to vary the effect of movement of the 45 charge controlling valve on the exhaust controlling valve.

11. The combination with an internal combustion engine having an exhaust passage, intake manifold and charge forming device 50 connected thereto, of a heater for heating the charge in its passage to the engine, said exhaust passage being provided with an opening upon one side and a boss upon the other side, a valve insertable through said 55 opening having a valve stem mounted in said boss, a cover for closing said valve, a bell crank loosely mounted on said valve stem, means for holding said bell crank in frictional engagement with said boss, a slotted 60 lever fixed on the end of said valve stem, an arm pivotally mounted on said bell crank a member carried by said arm working in

the slot of said lever, a valve controlling the passage of explosive charge to said engine, a connection between said charge throttling valve and said arm and dash controlling means having a connection with said bell 70 crank for adjusting the position of said member within said lever to vary the effect of movement of the charge controlling valve on the exhaust controlling valve.

12. The combination with an internal combustion engine, of an exhaust manifold, intake manifold and charge forming device connected thereto, a throttle valve in said intake manifold, said intake manifold being provided with heating chambers in communication at their upper ends with said exhaust manifold, a chamber surrounding the throttle chamber of said charge forming device forming a passage from one of said heating chambers to the other to allow said exhaust gases to pass downwardly through one of said chambers to the chamber of said charge forming device and up the other chamber, a double valve for controlling the passage of exhaust gases through said chambers, a slotted lever carried by said valve, a member slidably mounted in said slotted lever, a connection between said member and the charge throttling valve and means for adjusting said member in the slot of said lever to vary the effect of movement of the charge controlling valve on the exhaust controlling valve.

13. The combination with an internal combustion engine having an intake with a 100 throttle valve controlling the delivery of explosive mixture thereto, of an exhaust manifold having nipples for connecting the same to the exhaust ports thereof and an outlet at one end, said exhaust manifold having an auxiliary passage arranged to one side thereof and in communication with the main passage at one end provided with a valve controlled opening, the main exhaust passage being provided with an outlet and the auxiliary passage with an inlet, said passages being arranged at substantially the center of said manifold, a heater having separate chambers in communication with said inlet and outlet of said exhaust passage, a double 105 valve in said exhaust passages for controlling the passage of exhaust gases to and from said heater, a slotted lever carried by said double valve, a member slidably mounted in said slotted lever, a connection between said member and the charge throttling valve and means for adjusting said member in the slot of said lever to vary the effect of movement of the charge controlling valve on the exhaust controlling valve.

HOWARD M. CHAMBERS.
